UNITED STATES PATENT OFFICE.

ALBERT J. MYER, OF LAKE VIEW, NEW YORK.

RETARDING MECHANISM FOR ELEVATORS.

No. 882,577.

Specification of Letters Patent. Patented March 24, 1903.

Application filed August 9, 1905, Serial No. 273,435. Renewed June 10, 1907. Serial No. 378,285.

To all whom it may concern:

Be it known that I, ALBERT J. MYER, a citizen of the United States, residing at Lake View, in the county of Erie and State of New York, have invented a new and useful Improvement in Retarding Mechanism for Elevators, of which the following is a specification.

My invention relates to elevators and more particularly to means for regulating the speed of elevators and to safely arrest or stop the elevator car should it accidentally fall.

One of the objects of my invention has been to provide a simple device capable of being operated automatically by a liquid when applied to an elevator car.

In the accompanying drawings consisting of three sheets which form a part of this specification and in which like characters of reference indicate corresponding parts throughout the several figures: Figure 1 is a side elevation of an elevator car provided with my invention. Fig. 2 is a top plan view of the same. Figs. 3, 4, 5, 6 and 7 are sectional views of various forms of my cylindrical retarding mechanism. Fig. 8 is a top plan view of the means for supporting my cylindrical retarding mechanism. Fig. 9 is a side elevation of the same.

In the drawings, 1 is an elevator car movable up and down in a shaft on fixed vertical guides 2. On opposite sides of the elevator shaft there are also provided inclined guideways 3 and 4 which are inclined at any suitable angle to the vertical. In the accompanying drawings I have shown these guideways as converging toward the top of the shaft and diverging toward the bottom thereof, but it is evident that the reverse arrangement could be also employed to effect the results accomplished by my invention.

At the top of the elevator car 1, brake beams 5 and 6 are pivotally anchored to stay rods 7 and 8 at opposite sides of the car and these stay rods are suitably secured to the bottom of the said car. The pivot points 9 and 10 are preferably so positioned with reference to the guideways 3 and 4 that the brake beams 5 and 6 will be approximately in a perpendicular position with reference to the plane of the top of the car when the car is at the top of the elevator shaft and when the car is descending the said brake beams will

tend constantly to spread apart. The said brake beams are rectangular in shape and consist essentially of rods 11, which, as described, are pivotally secured at 9 and 10 to stay rods 7 and 8. Vertical supports 12 and 13 are rigidly secured to the rods 11 and these support the rods 15. The rods 15 carry at each end pivotally mounted rollers 16 and 17 which are adapted to travel in the two oppositely placed guideways 3. At any convenient place or places on the rods 15, I mount my cylindrical retarding mechanism 18. In Fig. 2 I show two such retarding mechanisms thus mounted but it is evident that one or more of the same could be thus mounted depending on the size of the cylinders used and the brake power desired. The guideways 3 and 4 in which the rollers 16 and 17 are adapted to travel, may be made of two plates with an intervening space or of a single grooved plate. In either case however, they are so constructed that the rollers are free to travel in the groove of the guideways.

The cylindrical retarding mechanisms may be of various different constructions. Thus in Fig. 4 I have shown a retarding mechanism provided with piston-heads 48, which do not fit tight in the cylinder 21. These piston-heads are mounted on the rods 19 which are adapted to move back and forth through the stuffing boxes 20. The cylinder 21 is provided with an inlet 22 through which the liquid used therein is introduced. When the cylinder 21 is filled with a liquid it will be evident that the speed of travel of the piston-heads 48 will be proportionate (1) to the space between the circumferences of the piston-heads and the cylinder walls, and (2) to the inertia of the liquid used.

In Fig. 5 is represented a retarding mechanism having piston-heads 23 which fit snugly in the cylinder 21 but are provided with perforations 24. In other respects this construction is like that shown in Fig. 4. Manifestly when the cylinder 21 is filled with a liquid the speed of travel of the piston-heads 23 will depend (1) on the size of the perforations 24 and (2) on the inertia of the liquid used.

In Fig. 6 solid piston-heads 25 fit closely in the cylinder 26. The upper wall of the cylinder 26 is provided with a passage 27

through which the liquid is capable of flowing from either end of the cylinder 26. Connecting the passage 27 with the center of the cylinder 26 is another passage 28 which is governed by a valve 29. Through the passage 28 the liquid may be introduced into the cylinder at 30 and the same may be closed on the outside by any suitable means. In this construction, the speed of travel of the piston-heads 25 will be governed (1) by the size of the passageways 27 and 28, (2) by the inertia of the liquid used and (3) by the position of the valve 29. If the valve 29 is so turned as to close the passageway 28 obviously no liquid can pass through either of the passageways and the piston-heads 25 will be brought to a stop.

Fig. 7 illustrates a construction in every respect like that shown in Fig. 6 except that a reservoir 31 is provided for containing a reserve quantity of liquid and the passageway 28 leading thereto is provided with a check valve 32 adapted to close when there is an upward pressure exerted against it and thus prevent the liquid from traveling from the cylinder back to the reservoir.

Fig. 3 represents a construction identical with that shown in Fig. 7 except that the rods 33 are provided with cone frustums 34 which are adapted to engage in the openings 35 in the diaphragms 36. These cone frustums are of such a size that when seated, they will closely fit in the openings 35 and from that size they taper to the diameter of the rod 33. In this construction the speed of travel of the piston-heads 25 depends on (1) the size of the opening 35 in the diaphragm 36, (2) the size of the passageway 27 and (3) the inertia of the liquid used. Moreover it is evident that the speed of travel of said piston-heads will be decreased as soon as the cone frustums enter the openings 35 and that their travel will stop when said frustums are fully seated in said openings.

In Fig. 2 I have shown my retarding mechanisms mounted on the brake beams and supported entirely thereon by the rods 37. While the construction therein illustrated is practical, a preferable construction is shown in Figs. 8 and 9. In the last mentioned figures, 38 is a table which carries my retarding mechanism 18 and which is adapted to move up and down the guiding supports 40 which are suitably secured to the tops of the elevator cars. Each of the supports 40 at its upper end has pivotally mounted on it a grooved wheel 41 over which a rope or chain 42 is adapted to travel. One end of said rope or chain is secured at 43 to the table 38 and to the other end is secured a weight 44. The weights 44 are so proportioned that they will just balance the table 38 and the retarding mechanisms carried thereon. The valve 29 of the cylinder 26 is provided with an arm

45 which is placed in contact with a vertical rod 46 secured in any suitable way to the table 38. On the top of the elevator car I provide a stop 47 against which the rod 46 is adapted to strike when the table 38 is sufficiently lowered. When the rod 46 does strike the stop 47 the arm 45 will be so thrown that it will close the valve 29 and thus prevent further travel of the piston-heads 25.

Having thus described the several parts of my invention, I will now describe its method of operation. Whenever the elevator car moves the friction rollers 16 and 17 will travel in the inclined guideways 3 and 4 and cause the rods 19 of my retarding mechanisms to drive back and forth in regular strokes the piston-heads of the cylinders.

As heretofore explained the speed of travel of the piston-heads of whatever construction they may be as herein illustrated will depend on the passageway allowed for the passage of the liquid and the inertia of the liquid. The maximum speed of the car therefore will depend on the size of the passageway allowed for the travel of the liquid used in the cylinders so that as long as the predetermined maximum speed of the car is not exceeded, the friction of the rods 16 and 17 on the walls of the guideways 3 and 4 will not retard the motion of the car. But if the predetermined maximum limit of speed of the car is reached or attempted to be passed,

the inertia of the liquid in passing through the space allowed for it will so retard the movement of the piston-heads as to cause the rollers 16 and 17 to bind against the guideways 3 and 4 with so much force that the movement of the car will be retarded. Again if the car is out loose from its cable and allowed to fall, the speed of the car will be limited by the inertia of the fluid and the size of the passageway allowed for it. Thus it will be noted that my retarding mechanism is continually in operation when the elevator is moved and acts to govern the speed of the elevator at all times, thus very greatly lessening the possibility of accidents.

It is obvious that as the car moves downwardly the brake beams 5 and 6 will be thrown outwardly and will carry with them the rods 37 which move the piston-heads in the cylinders 18. This movement of the brake beams will depend on the friction caused by the friction rollers 16 and 17 traveling in the inclined guideways 3 and 4 and it is apparent that with the construction shown in Figs. 8 and 9 the elevator car will be brought to a stop when the rod 46 comes in contact with the stop 47 and causes the arm 45 of the valve 29 to move so as to close the valve and thus prevent further movement of the liquid in the cylinders. This movement of the rod 46 will obviously de-

pend on the position of the brake beams 5 and 6 which position as heretofore shown, controls the position of the table 38 which is raised and lowered by the movement of the 5 said brake beams.

Having thus described my invention and its method of operation, what I claim is:

1. A retarding mechanism for an elevator car comprising pivotally mounted means secured to said car, inclined guideways secured to the elevator shaft, friction producing means which are adapted to travel in said inclined guideways and are carried by said pivotally mounted means, and means, supported by said pivotally mounted means, for governing the said friction producing means.

2. A retarding mechanism for an elevator car comprising brake beams pivotally mounted to said car, rollers pivotally mounted on 20 said brake beams, inclined guideways in which said rollers are adapted to travel, a fluid governed cylinder supported by said brake beams, piston-heads in said cylinder, means connecting said piston-heads with 25 said brake beams and means for governing the speed of travel of said piston-heads.

3. A retarding mechanism for an elevator car comprising pivotally mounted brake beams secured to the car, inclined guideways 30 secured to the elevator shaft, friction producing means carried by said brake beams and adapted to travel in said inclined guideways, a fluid containing cylinder, piston-heads adapted to travel in said cylinder, 35 means for governing the speed of travel of said piston-heads in said cylinder and means for connecting said piston-heads with said brake beams.

4. A retarding mechanism for an elevator car comprising pivotally mounted brake 40 beams secured to the car, inclined guideways secured to the elevator shaft, friction producing means carried by said brake beams and adapted to travel in said inclined guideways, a fluid containing cylinder, piston-heads closely fitting said cylinder and adapted to travel therein and means for connecting said piston-heads with said brake beams.

5. A retarding mechanism for an elevator 50 car comprising pivotally mounted brake beams secured to the car, inclined guideways secured to the elevator shaft, friction producing means carried by said brake beams and adapted to travel in said inclined guideways, a fluid containing cylinder, piston-heads closely fitting said cylinder and adapted to travel therein, valve controlled means for allowing the passage of fluid in said cylinder from the ends to the center thereof or 55 oppositely as the said piston-heads move back and forth therein and means for connecting said piston-heads with said brake beams.

6. A retarding mechanism for an elevator 60 car comprising pivotally mounted brake

beams secured to the car, inclined guideways secured to the elevator shaft, friction producing means carried by said brake beams and adapted to travel in said inclined guideways, a fluid containing cylinder, piston-heads closely fitting said cylinder and adapted to travel therein, valve controlled means for allowing the passage of fluid in said cylinder from the ends to the center thereof or oppositely as the said piston-heads move 70 back and forth therein, a reservoir secured to the said cylinder, a check valve for preventing the fluid from traveling from said cylinder to said reservoir and means for connecting said piston-heads with said brake beams.

7. A retarding mechanism for an elevator car comprising pivotally mounted brake beams secured to the car, inclined guideways secured to the elevator shaft, friction producing means carried by said brake beams and adapted to travel in said inclined guideways, a fluid containing cylinder, piston-heads closely fitting said cylinder and adapted to travel therein, fixed diaphragms provided with vents and located between said piston-heads and the ends of said cylinder, cone frustums mounted on piston rods and adapted to be seated in the vents on said fixed diaphragms, valve controlled means 85 for allowing the passage of fluid in said cylinder from the ends to the center thereof or oppositely as the said piston-heads travel back and forth therein, and piston rods connecting the said movable rods with said 90 brake beams.

8. A retarding mechanism for an elevator car comprising pivotally mounted brake beams secured to the car, inclined guideways secured to the elevator shaft, friction producing means carried by said brake beams and adapted to travel in said inclined guideways, a fluid containing cylinder, piston-heads adapted to travel in said cylinder, means for governing the speed of said piston 105 heads in said cylinder, piston rods connecting said piston-heads with said brake beams and means secured to the elevator car adapted to travel in consonance with the travel of said brake beams for supporting said cylinder.

9. A retarding mechanism for an elevator car comprising pivotally mounted brake beams secured to the car, inclined guideways secured to the elevator shaft, friction producing means carried by said brake beams and adapted to travel in said inclined guideways, a fluid containing cylinder, piston-heads closely fitting said cylinder and adapted to travel therein, valve controlled means 120 for allowing the passage of the fluid in said cylinder from the ends to the center thereof or oppositely as the said piston-heads move back and forth therein, a valve located in said last mentioned means for controlling 125

the passage of the liquid therethrough, piston-rods for connecting said piston-heads with said brake beams, and a valve governing means for closing said valves as said 5 brake beams reach the limit of their outward travel.

In testimony whereof, I have hereunto

subscribed my name in the presence of two witnesses.

ALBERT J. MYER,

Witnesses:
